UNITED STATES PATENT OFFICE.

CHARLES MAGEE, OF BROOKLYN, NEW YORK, ASSIGNOR TO THE BIGELOW CARPET COMPANY, OF CLINTON, MASSACHUSETTS.

DESIGN FOR A CARPET.

SPECIFICATION forming part of Design No. 13,702, dated March 6, 1883.

Application filed December 12, 1882. Term of patent 3½ years.

To all whom it may concern:

Be it known that I, CHARLES MAGEE, of Brooklyn, in the county of Kings and State of New York, have invented a new and original Design for Carpets, of which the following is a specification.

This invention relates to a new and original design for carpets and similar fabrics; and it consists in the novel grouping and configuration of parts, hereinafter more fully described.

The accompanying photograph illustrates a face view of a carpet having my new design. B is a stripe containing ornamentation composed of a curving flower-like figure, c, alternating with figure b, resembling a flower springing from a curving leaf. Below the stripe B is a band, h, containing ornamentation of circular figures set at intervals. The stripe D contains a group, C, composed of circular flower-like figures t t, which form the base for a sort of pyramid, of which the similar circular figure s forms the top, and on each side of the figure s is a figure, r, somewhat resembling an open rose, the whole being surrounded and entwined with branches and leaves. The group E, in the same stripe, is composed of a leaf-like figure, v, above which appear a couple of star-flowers, e, and above these, on

each side, are two curving branches, j j, bearing leaves. These two groups alternate along the stripe. The band F contains circular figures x, set at intervals, a series of arched figures, y, along its top, and a zigzag ornamentation, z, along its bottom portion.

I claim—

1. The design for carpets, consisting of the stripe B, containing figures b and c, substantially as shown.
2. The design for carpets, consisting of the stripe B, containing figures b and c and band h, substantially as shown.
3. The design for carpets, consisting of the stripe D, containing figures r s t v e j, substantially as shown.
4. The design for carpets, consisting of the band F, containing figures y x z, substantially as shown.
5. The design for carpets, consisting of the stripe B, containing figures b c, band h, stripe D, containing figures r s t v e j, and band F, containing figures x y z, substantially as shown.

CHARLES MAGEE.
